UNITED STATES PATENT OFFICE.

JOHN R. BARKER, OF CHICAGO, ILLINOIS.

HOT-AIR FURNACE.

SPECIFICATION forming part of Letters Patent No. 326,541, dated September 22, 1885.

Application filed November 19, 1884. (No model.)

To all whom it may concern:

Be it known that I, JOHN R. BARKER, a citizen of the United States of America, residing at Chicago, in the county of Cook and State of Illinois, have invented certain new and useful Improvements in Hot-Air Furnaces, of which the following is a specification, reference being had therein to the accompanying drawings.

10 My invention relates to an improved radiator or hot-air furnace.

The object of the invention is to improve the general construction of such furnaces in order to obtain the most beneficial results; and 15 to the accomplishment of that end the invention consists of the novel devices and combination of devices, as will be described.

Reference will be made to the accompanying drawings, in which Figure 1 is a vertical section of the radiator complete; Fig. 2, a detail plan view of the upper portion of the air-escape; Fig. 3, a detail of the ring forming the uppermost gas-chamber; Fig. 4, a plan of a ring completing such upper gas-chamber and 20 dividing it from a lower chamber; Figs. 5 and 6, details showing rings forming side walls of lower chamber, upon which parts shown in Fig. 4 are supported; Fig. 7, a view of a dome situated within the lower gas-chamber and 25 dividing it from a lower chamber; Figs. 5 and 6, details showing rings forming side walls of lower chamber, upon which parts shown in Fig. 4 are supported; Fig. 7, a view of a dome situated within the lower gas-chamber and 30 resting upon the main dome, of which Fig. 8 is a detail view; Fig. 9, a view of a ring situated between the fire-pot and main dome and adapted to admit air to the fire-space; Fig. 10, a section on line 1 1 of Fig. 9; Fig. 11, a detail of the vapor-pan used; Fig. 12, a detail of a removable piece used to allow access to parts of the radiator; and Fig. 13, a section on lines 2 2 of Figs. 7, 8.

Like letters refer to like parts in each view. 40 A represents the outer casing, supported upon suitable legs, *a*, a sufficient distance above the floor to admit air to its interior, and at its upper end is provided with openings *b* for hot-air pipes.

45 B represents the ash-pit, and C the grate, the ash-pit being partly surrounded by a vapor-pan, D, suitably supported, and of the shape shown.

E is the fire-pot, and F the lower dome, the 50 walls of the fire-pot and dome being separated by ring G. This ring is provided with down-

wardly opening ports *c*, Fig. 10, through which air is admitted to passage *d*, extending entirely around the ring, and communicating with the interior of the combustion-chamber 55 through openings *e*, through which the air entering ports *c* passes to the combustion-chamber, where it commingles with the gases arising from the fire-bed and is ignited.

Formed upon the upper face of dome F are 60 flues H H J, which communicate with corresponding flues, K K L, with which the upper dome, M, is provided. The gases from the fire-bed pass through these flues to gas-chamber N, while the hot air passes around the flues 65 up through the flaring tube O, supported as shown, and thence to the hot-air pipes leading to the parts to be heated. The gases and smoke which pass through the flues circulate and are retained for a short period in chamber 70 N, and pass through openings *f f*, formed in partition P, to the second gas-chamber Q, where they are forced to pass around the tube O, situated in such chamber, before passing off through the chimney R, which communicates with chamber Q. By this arrangement 75 it will be seen that the gases are sufficiently retarded to be entirely consumed before passing to the chimney and the full benefit of the heat obtained.

Formed upon ring G, hereinbefore referred to, is a flange, S, which projects outwardly a short distance beyond the walls of the combustion-chamber, and which is provided with a series of openings, *g*. By means of this arrangement the air arising from the bottom of the furnace is slightly retarded in its upward flow, and serves to draw sufficient heat from the parts to add greatly to their utility and durability. Similar flanges are formed upon 85 the base of the lower gas-chamber, upon the outer edge of the partition forming the base of the upper gas-chamber, and upon the upper outer edge of tube O.

In the side walls of the gas-chambers suitable openings are formed, as shown at *h*, Figs. 4, 5, 6, and through which access may be gained to said chambers for the purpose of cleaning, &c., such openings being in a line with door T.

100 The openings *h*, above referred to, are adapted to be closed, when access is not de-

sired, by a piece, W, (shown in detail in Fig. 12,) and which is adapted to be removed when it is desired to gain access.

X' represents a door leading to the combustion-chamber, and Y a similar door leading to the space occupied by the vapor-pan.

What I claim is—

In a hot-air furnace, the combination, with the walls of fire-space E and dome F, of the interposed ring G, such ring provided with a

perforated flange, and suitable ports to admit air to the interior of the combustion-chamber, as set forth.

In testimony whereof I affix my signature in presence of two witnesses.

JOHN R. BARKER.
